UNITED STATES PATENT OFFICE.

JOHN C. RECKWEG, OF LOS ANGELES, CALIFORNIA.

AIR-SHIP.

No. 852,239.

Specification of Letters Patent.

Patented April 30, 1907.

Application filed December 11, 1905. Serial No. 291,816.

To all whom it may concern:

Be it known that I, JOHN C. RECKWEG, a citizen of the United States, residing at Los Angeles, in the county of Los Angeles and State of California, have invented certain new and useful Improvements in Air-Ships; and I do declare the following to be a full, clear, and exact description of the invention, such as will enable others skilled in the art to which it appertains to make and use the same.

My invention relates to improvements in air ships and consists of certain novel features of construction, combination and arrangement of parts as will be hereinafter described and claimed.

The object of the invention is to provide a simple, practical and efficient means for steering and propelling air ships or bodies supported by a balloon or other gas field.

The above and other objects which will appear as the nature of my invention is better understood, are accomplished by means of the construction illustrated in the accompanying drawings, in which,—

Figure 1 is a side elevation of an air ship with my improved propelling and steering mechanism applied thereto; Fig. 2 is a horizontal sectional view taken on the plane indicated by the line 2—2 in Fig. 1; Fig. 3 is a vertical longitudinal sectional view through the parts shown in Fig. 2; Figs. 4, 5 and 6 are vertical transverse sectional views taken respectively on the planes indicated by the lines 4—4; 5—5 and 6—6 in Fig. 3; Fig. 7 is a detail view of the pivot bearing for one of the wings; and Figs. 8 and 9 are plan and sectional views of one of the valves in the coverings for the wings and rudder.

Referring to the drawings by numeral, 1 denotes the body of the air ship, which may be of any suitable form and construction, and which is adapted to be supported or floated by a balloon 2 or other gas field, which may be of any form and construction and connected to the body or ship 1 in any suitable manner. As shown, the body or ship 1 is in the form of a boat and consists of a skeleton frame 3, which is in the form of the hull of a boat and which may be covered if desired. This frame 3 comprises a plurality of substantially U-shaped ribs 4 arranged transversely in parallel relation and connected by a keel 5 and a surrounding upper rail or rim 6. The ribs 4 are strengthened by vertical posts 7, which are connected to each other by

a curved central brace 8 and to the upper portions of the ribs by transverse braces 9.

The air ship is adapted to be propelled and steered by means of a plurality of pairs of wings 10 and a fan-shaped rudder or tail 11. The wings 10 of each pair, of which there may be any number, are arranged upon opposite sides of the body 3 and are in longitudinal alignment, as shown. Each of the wings 10 consists of a frame 12 and a covering 13 of fabric or any other suitable material. The two side rods 14 of the frame 12 of each wing are brought together and united at their inner end 15, and they are pivotally mounted in bearings 16—17 provided upon the rail or rim 6. As clearly shown in Fig. 7 of the drawings, the bearing 16 is disposed at a greater elevation than the bearing 17, so that each wing will have an upward and rearward inclination to cause it to operate efficiently when oscillated. The inner ends 15 of the wings of each pair are loosely pivoted in a vertically reciprocating frame or slide 18, which is mounted in a suitable guide upon one of the central posts 7 and which has a transversely extending slot or elongated opening 19 formed therein to receive an eccentric 20 provided upon a longitudinally extending drive shaft 21. It will be seen upon reference to Fig. 4 of the drawings that when the shaft 21 is rotated, the eccentric 20 will cause the slide 18 to move up and down and simultaneously oscillate one pair of the wings 10.

The fan shaped rudder or tail 11 is mounted upon the rear end of the body 3 and comprises a cross-shape frame formed of two bars 22 connected by curved cross bars covered by a covering of fabric or other light material 23. The crossed bars 22, at their junction, are connected by means of a universal joint or bearing 24 to the rear end of the body 3 and their diverging inner ends 25 are connected by a cross bar 26, which is pivoted at its center as shown at 27 in a slide 28, which is similar to the slide 18. As clearly shown in Fig. 5 of the drawings, said slide 28 is slidably mounted in suitable bearings and is formed with an elongated opening to receive one of the eccentrics 20 upon the shaft 21, so that as the latter is rotated, the rudder or tail 11 will be oscillated. In order to tilt the curved outer end of the tail or rudder transversely and thereby steer the ship in the desired direction, suitable chains, cables or other flexible connections 29 are connected

to the ends of the cross bar 26, so that the latter may be swung upon its pivot 27 and will tilt the rudder angularly to either side. The operating connections 29 pass over suitable guide pulleys or devices 30 and may be operated by any suitable mechanism conveniently arranged where the operator is stationed.

The shaft 21 is preferably driven by a gasoline motor 31 suitably mounted within the body 3 and geared to the shaft in any desired manner. In Fig. 2 of the drawings, a gasoline tank 32 is also shown mounted within the frame. The eccentrics 20 are preferably so disposed upon the shaft 21 that the foremost pair of wings and the rudder will be simultaneously raised and lowered and the intermediate pairs of wings will be successively raised and lowered, so that the ship will be prevented from rocking and the motion will be like that of a bird.

In order to permit the wings 10 and rudder 11 to quickly ascend, I provide in their coverings 13 and 23, openings 33, which are controlled by valves 34, so that air will be permitted to pass therethrough upon their up-stroke but not upon their down-stroke. As shown, the openings 33 are circular in form and the valves 34 are of similar shape, said valves being also composed of fabric and strengthened by wires 35. The valves are hinged at one side and are held normally in their closed position, as shown in Fig. 9, by coiled springs 36, as will be readily seen upon reference to Fig. 8. As the wings descend, the valves 34 will close the openings 33 so that the air beneath the wings will offer a resistance thereto, and upon the up-stroke of said wings, said valves will open, as shown in dotted lines in Fig. 9, to permit the air to pass downwardly therethrough.

From the foregoing description, taken in connection with the accompanying drawings, the construction, operation and advantages of the invention will be readily understood without requiring a more extended explanation.

Various changes in the form, proportion and the minor details of construction may be resorted to without departing from the principle or sacrificing any of the advantages of this invention.

Having thus described my invention, what I claim as new and desire to secure by Letters-Patent is:—

1. An air ship comprising a body, oscillating wings arranged in pairs and pivotally mounted upon the opposite sides of said body, a rudder pivotally mounted at the rear end of said body, vertically reciprocating slides in said body pivotally connected to the inner ends of said wings and said rudder, a longitudinally extending shaft, and eccentrics upon said shaft for actuating said slides.

2. An air ship comprising a body, oscillating wings arranged in pairs and pivotally mounted upon the opposite sides of said body, a rudder pivotally mounted at the rear end of said body, vertically reciprocating slides in said body pivotally connected to the inner ends of said wings and said rudder, a longitudinally extending shaft, eccentrics upon said shaft for actuating said slides, and means for tilting said rudder angularly.

3. An air ship comprising a body, a fan-shaped rudder mounted to swing vertically and rotate axially upon the rear portion of said frame, diverging arms or ends at the inner portion of said rudder, a vertically reciprocating slide, a cross bar pivoted centrally in said slides and having the inner ends or arms of said rudder secured in its ends, a shaft, an eccentric upon said shaft for reciprocating said slide, and operating connections attached to the ends of said cross bar to swing the latter and hence said rudder axially.

In testimony whereof I have hereunto set my hand in presence of two subscribing witnesses.

JOHN C. RECKWEG.
